UNITED STATES PATENT OFFICE.

WILLIAM T. WATERS, OF ATLANTA, GEORGIA.

ELECTRIC RAILWAY-SIGNAL.

SPECIFICATION forming part of Letters Patent No. 314,761, dated March 31, 1885.

Application filed May 23, 1883. (No model.)

To all whom it may concern:

Be it known that I, WILLIAM T. WATERS, of Atlanta, in the county of Fulton and State of Georgia, have invented a new and useful Improvement in Electric Railway-Signals, of which the following is a full, clear, and exact description.

Reference is to be had to the accompanying drawings, forming a part of this specification, in which similar letters of reference indicate corresponding parts in all the figures.

Figure 1, Sheet 1, is a plan view of a portion of a railroad-track, showing a series of posts and their conducting-wire upon each side of a track. Fig. 2, Sheet 1, represents a number of the posts in their regular order, but turned one-quarter around to more clearly illustrate the electrical connections. It also indicates the position of a train and the relative positions of the signals with respect thereto. Fig. 3, Sheet 1, is a front elevation, partly in section, of a part of a locomotive, showing the batteries, battery-connections, insulated contact-bars, and inclined push-bar. Fig. 4, Sheet 2, is a sectional view of one of the posts, showing the mechanism for raising the signals. Fig. 5, Sheet 3, is a sectional view of a signal-box, showing an advance signal concealed and the mechanism for holding it. Fig. 6, Sheet 3, is a sectional view of a signal-box, showing a rear signal and a part of the mechanism for raising it. Fig. 7, Sheet 3, is a front elevation of a signal-box, showing the signals and relief-lever in edge view. Fig. 8, Sheet 3, is a sectional plan view of the same. Fig. 9, Sheet 4, is a front elevation of a part of a signal-box, showing a crossing signal and its gong. Fig. 10, Sheet 4, is a sectional view of the same taken through the line *x x*, Fig. 9. Fig. 11, Sheet 4, is a sectional view of the same taken through the line *y y*, Fig. 9. Fig. 12, Sheet 4, is a plan view of a locomotive, showing the insulated contact-bars and the inclined push-bars, and Fig. 13 is a detail sectional view.

The object of this invention is to improve the construction of the electric railway-signals for which an application for Letters Patent was filed by me January 27, 1883, No. 83,272.

The invention consists in the combination of switches and other appliances with the op-

erating mechanism of the signals, to make the said signals more satisfactory and effective in use, as will be hereinafter fully described, and pointed out in the claims.

55

A represents an ordinary railroad-track, along each side of which is erected a series of posts, *B*, at uniform or unequal distances apart, as may be desired or convenient.

To each post *B*, or to suitable independent supports, or to supports secured to each post, are attached two pairs of conducting-arms, *C D* and *C' D'*, above the ground. All the pairs of each series are at the same distance from the vertical plane of the central line of the track *A*, and may or may not be at the same height above the level of the said track. The bases of the arms *C D* are insulated from each other and from their supports, and each arm *C* is made elastic and longer than each 70 arm *D*, as shown in Fig. 4.

From each arm *C'* a wire, *E*, leads to the arm *C* of the next forward post, *B*, as shown in Fig. 2. To each arm *D* is attached the end of a wire, *F*, the other end of which is connected with the end of the coil of the magnet *G*, attached to the post *B*. The other end of the coil of the magnet *G* is connected with the end of the wire *H*, the other end of which is connected with the switch *I*. When the advance signal *J*, which is pivoted at its lower end in a recess in the post *B*, or in a box attached to the said post, is concealed or raised, the switch *I* is connected with the contact-point *K*, connected with the upper end of the ground-wire *L*. As the electric current passes through the circuit thus formed the magnet *G* attracts the armature *M* and withdraws the hook or shoulder *N*, formed upon the said armature, from the hook *O*, formed upon the 90 end of the curved lever *P*, as shown in Fig. 5, and allows the advance signal *J* to be swung down or displayed by the weight *Q*, attached to or suspended from it, the said advance signal being locked in place when raised by the engagement of a slot, *R*, in the projecting middle part of the curved lever *P*, with a pin, *S*, attached to the advance signal *J* near the inner corner of its free end, as shown in Fig. 5. As the armature *M* moves into contact 100 with the magnet *G* it brings the end of the wire or conducting-strip *T*, as shown in Fig.

5, into contact with the switch U. The wire or strip T is connected with the armature M, so as to be carried by the said armature M in its movements, and its other end is connected 5 with the conducting-wire H. The switch U is attached to the post B, or to a support attached to the said post. With this construction, as the current of electricity passes through the magnet G and drops the advance signal J, 10 the wire T and switch U are brought into contact, and the current of electricity passes through the said wire and switch to the ground-wire L, instead of passing through the wire H and switch I. The object of the switch 15 U, therefore, is to provide a temporary ground-connection for an advance current, which would otherwise be diverted through the wire W to the next post in advance, and if sufficiently long maintained would drop signal 20 after signal indefinitely. By the use of this switch a single current can drop but one signal, though not always necessarily the first signal in advance, but always the first advance signal that has not already been displayed, as hereinbefore set forth. The switch 25 U may be a ground-connection only when the advance signal J is at "safety." In other words, it forms a ground-connection only for the current that releases the advance signal 30 with which it is connected. As the advance signal J drops into a horizontal position, its rounded lower end comes in contact with the switch I and pushes the said switch out of contact with the contact-point 35 K and into contact with the contact-point V, with which is connected the end of the wire W. The other end of the wire W is connected with the circuit-wire E. The switch U is made elastic, and is so formed that the switch 40 I, as it moves from the contact-point K to the contact-point V, will put the switch U under tension, so that when the armature against which the free end of the said switch is pressed rises at the interruption of the current the 45 said switch will spring forward against the stop X, and will be held there so long as the advance signal is displayed, and when in this position cannot be touched by the wire or strip T, carried by the armature M. The switches 50 I, U are insulated from each other at the point where they come in contact in pushing forward the switch U. With each arm D' is connected the end of a wire, F', the other end of which is connected with one end of the coil of the 55 magnet G'. The other end of the coil of the magnet G' is connected with a switch, I', placed in such a position that when the rear signal, J', is raised or displayed its rounded pivoted end will force the said switch into 60 contact with the point a, from which a wire, L², leads to the ground-wire L. With this construction, when the arm C is raised from the arm D and brought into the circuit, the current of electricity will pass to the rearward 65 through the wire E, to and through the contact-arms C' D', and thence through the wire F', the coil of the magnet G', the switch I',

the contact-point a, and the wires L² L to the ground, and when the arm C' is raised from the arm D' and brought into circuit the current of electricity will pass forward through the wire E to and through the contact-arms C D of the next post, and thence through the wire F, the coils of the magnet G, to the wire H. From this point the direction of the current is controlled by the position of the advance signal J. If the advance signal be held at "safety," the current will pass from the wire H to the switch I, contact-point K, thence to the ground, as hereinbefore described; but if the 75 advance signal be displayed a current passing from the wire H through the switch I and contact-point V will pass through the wire W and line-wire E, the arms C D of the next post in advance, and thence through the wire 80 F, coils of magnet G, the wire H, switch I, contact-point K, and thence to the ground. By means of the wire W and the system of switches herein set forth not only one, but 85 two or more signals may be displayed in advance of the moving train. By the use of the switch I' the ground-connection at contact-point a is maintained only while the signal 90 J' is displayed. When the signal J' is concealed, the switch I', having no ground-connection, will not afford an escape for an advance current passing from the wire W. As the electric current passes through the coil 95 of the magnet G' the said magnet attracts the armature M', withdrawing its hook N' from the hook O' of the lever P', releasing the rear signal, J', and allowing the said signal to drop into a vertical position and out of sight by its own weight. (See Fig. 4.) The lever P' is pivoted at the inner part of its upper end to 100 the post or box B, and in the outer edge of its 105 said upper end is formed a semicircular recess, b, as shown in full lines in Fig. 4 and in dotted lines in Fig. 6. In the outer edge of the upper end of the lever P', at the bottom 110 of the recess b, is formed a slot, c, to receive a pin, d, attached to the signal J'. With this construction, as the lever P' is released from the armature M' the descent of the signal J' forces the pin d against the upper edge of the 115 slot c, and swings the lower end of the said lever P' outward, so that the pin d will pass out of the slot c, and will move along the upper part of the curved edge of the recess b nearly to the upper end of the said curve, the 120 said curve being so formed as to allow the lower end of the said lever P' to swing back into the post or box B. As the signal J' is raised the pin d moves back along the curved edge of the recess b until it reaches and enters 125 the slot c, when it presses against the lower edge of the said slot, so as to swing the lower end of the lever P' so far inward as to bring the hook O' into position to engage with the hook N' of the armature M', again locking the 130 said signal in place.

In the case of a crossing, e, or other dangerous locality, a post adjacent to or at any desired distance from the said crossing is pro-

vided with a third pair of conducting-arms, C² D², placed below the arms C' D', and having the end of a wire, F², connected with the upper arm, C². The other end of the wire F² is connected with the end of the coil of a magnet, G², attached to a special post, B', placed near the crossing e, and provided with a hooked armature, M², to hold and release a special signal, J², which is constructed and operated in the same manner as an advance signal, J, except that no switches are required.

With the special post B' is connected a local battery, f, the circuit-wires g' g of which are connected with a gong, h, also attached to the special post B', as shown in Fig. 2. In this case one of the conducting-wires g' g is divided, and the adjacent ends of its parts are connected with contact-points i i'.

To the pivot of the signal J² is attached a switch, j, in such a position that it will be brought into contact with the points i i' to close the circuit and sound the gong when the signal J² is displayed, and will be withdrawn from the said points to open the circuit when the said signal J² is concealed. In case a post, B, is placed near the crossing e, a special signal, J³, is connected with the pivot of the advance signal, J, so as to be operated by and with the said signal J. The signal J³ can be made rectangular, as shown in Figs. 9 and 10, or of any other suitable form, so as to display a danger-signal when the signal J is displayed, and a safety-signal when the signal J is concealed, and thereby avoid the expense of an extra post. The special signal J³ may be made short and supported wholly by the post B, or it may extend across the roadway and be pivoted at its other end to a special post, B'. In this case the local battery f, gong h, circuit-wires g' g, and switch j i i' can be connected with the special post B' and the outer pivot of the signal J³, as shown in Fig. 9.

When the signals J J³ are heavy, a disk, k, can be attached to the pivot of the said signals, and provided with a hook or shoulder, l, to engage with the hook N of the armature M, the magnet G in this case being placed near the pivoted end of the signal J, and the lever P not being used, as shown in Figs. 9 and 11.

To the disk k is attached a weight, m, in such a position that its gravity will start the signals J J³ in their movement when released by the action of the magnet G upon the armature M.

Upon the engine r, or any desired car of the train, are placed three separate batteries, o o' o'', the negative poles of which are connected by wires p p' p'' with the running-gear of the engine, which, in connection with the rails of the track A, forms the ground-connection. The positive poles of the batteries o o' o'' are connected, respectively, by wires q q' q'' with projecting bars r r' r'', insulated from the side 65 of the engine or car in such positions as to come in contact successively with the lower

sides of the projecting ends of the upper arms, C C' C'', and raise the said arms out of contact with the lower arms, D D' D''. With this construction, when the engine n, or the car to which the bars r r' r'' are attached, comes opposite each post B, the bars r r' come successively in contact with and raise the arms C C'. As each arm C is raised the electric current from the battery o' will pass through the wire q', the bar r', the arm C', and the wire E to the post B, with which the other end of the said wire is connected, where it will release one or more advance signals, J, in the manner hereinbefore described, and allow them to drop into view, and will then pass to the ground. As each arm C is raised the electric current from the battery o will pass through the wire q, the bar r, the arm C, and the wire E back to the post B, with which the other end of the said wire is connected, where it will release the rear signal, J, in the manner hereinbefore described, and allow it to drop out of view, and will then pass to the ground. As the engine or car passes each post provided with a third pair of arms, C² D², the bar r'' comes in contact with and raises the arm C², and the electric current from the battery o² passes through the wire q'', the bar r'', the arm C², and the wire F² to the post B', with which the other end of the said wire is connected, where it will release the special signal J² and allow it to drop into view, and will then pass to the ground. The ends of the bars r r' r'' are inclined downward, so that they will readily pass beneath and raise the ends of the arms C C' C''. And the said bars r r' r'' are made of such a length as to maintain a contact with the said arms C C' C'' long enough to allow the electric current to do its work. The wires q q' are divided, and the ends of the parts next the batteries o o' are connected with the switches s s'. The adjacent ends of the other parts of the wires q q' are connected with the contact-points t t' of the switches s s'. With other contact-points, u u', of the switches s s' are connected wires v v', which pass to the other side of the engine or car, and are connected with a set of insulated contact-bars, w w', similar to the bars r r', so that the signals can be operated from either side of the said engine or car, as one or the other side may be toward the posts B.

To the journals of the signals J J' are pivoted the ends of connecting-bars x x', the other ends of which are pivoted to horizontally-slotted arms y y', attached to a vertical rod, z. The rod z slides vertically in bearings in the box or post B, and is raised and held up by a spiral spring, 1, placed upon its upper part. The upper end of the spring 1 rests against a pin, 2, passed through a collar attached to the said rod near its upper end. The lower end of the spring 1 rests upon a stationary support, 3, attached to the box or post B, and through which the rod z slides.

To the lower end of the rod z are attached spring clutch-jaws 4 to receive and engage

with the spear-head 5 when the short rod 6, to which the said spear-head is attached, or upon which it is formed, moves upward. The lower end of the rod 6 is attached to a weight, 7, which is made hollow, and is placed and slides upon the upper part of the rod 8, which passes up through the lower end of the weight 7, and has a head, 9, upon its upper end, so that it can move down without carrying the said weight with it.

To the lower end of the rod 8 is attached a pin, 10, which passes through a longitudinal slot, 11, in the outer end of the long arm of the elbow-lever 12. The lever 12 is pivoted at its angle to the post B, or other suitable support, and its short arm is widened or branched, and has a three-armed slot, 13 14 15, formed in it to receive the pin 16, attached to the end of the horizontal rod 17, which slides in bearings in posts 18, or other stationary supports, placed between the posts B and the railroad-track A. The sliding rod 17 is brought into and held in its normal position by two spiral springs, 19 20. The spring 19 is placed upon the rod 17, between the outer and central posts 18, with its outer end resting against the outer post 18, and its inner end resting against a pin, 21, attached to the said rod at the outer side of the central post 18. The spring 20 is placed upon the inner part of the rod 17, with its outer end resting against a pin, 22, attached to the said rod 17 at the inner side of the central post 18, and with its inner end resting against the outer side of the inner post 18, as shown in Figs. 4 and 12. The bearing in the central post 18 is slotted to allow the pins 21 22 to pass the central post. With this construction, as the rod 17 is forced outward the pin 22 slides through the slot in the bearing and the pin 21 is forced against the end of the spring 19 and compresses it, so that the said rod, when released, will be brought back to its normal position by the elasticity of the said spring 19. When the rod 17 is forced inward, the pin 21 slides through the slot in the bearing and the pin 22 is forced against the end of the spring 20 and compresses it, so that the rod 17, when released, will be brought back to its normal position by the elasticity of the spring 20. In either case the rod 17 slides freely through the spring that is not put under compression.

To the inner end or head of the rod 17 is pivoted a small roller, 23, to be struck by an inclined push-bar, 24, connected with the engine by arms or brackets 25. With this construction, as the engine n moves forward the inclined push-bar 24 strikes against the inner side of the roller 23 and pushes the rod 17 outward, which movement operates the elbow-lever 12, raises the rod 8 and weight 7, bringing the spear-head 5 of the rod 6 into contact with the clutch-jaws 4, attached to the lower end of the sliding rod z. As the inclined push-bar 24 passes off the roller 23 the spring 19 forces the rod 17 inward, draws the rod 8

downward, and allows the weight 7 to draw the sliding rod z downward and raise the signals, with which the said rod is connected, from a horizontal to a vertical position, or from a vertical to a horizontal position, or, in other words, conceals an advance or crossing signal and displays a rear signal, so that the signals will always be raised by mechanical means and released and allowed to drop by the action of an electric current, as hereinbefore described.

As the rod z is drawn downward by the weight 7 the bars x x', connected with the slotted arms y y', attached to the said rod, are drawn against the pins 26, or other stops formed upon or attached to the signals or signal-operating disk, and act as cranks to raise the said signals. As the signals come into position and the rod z reaches the limit of its downward movement the jaws 4 come in contact with the pins 27, attached to the post or box B, and are forced apart, releasing the head 5 of the rod 6 and allowing the weight 7 to continue its downward movement until it comes in contact with the stops 28, attached to the box or post B, and which support the said weight until again raised by the upward movement of the rod 8.

To the rod 8 is attached a collar, 29, having a rubber cushion, 30, placed upon it to come in contact with the lower end of the weight 7 as the said rod 8 moves upward, and prevent any injurious shock from the sudden contact of the moving rod with the stationary weight, the said weight receiving its initial upward movement from the elasticity of the said cushion 30. When the engine is moved backward, the outer end of the inclined push-bar 24 will pass upon the outer side of the roller 23, and will draw the rod 17 inward, the pin 16, at the outer end of the said rod, moving into and along the slot-arm 15 of the three-armed slot in the short arm of the elbow-lever 12, so that the said lever 12 will not be moved. Inclined push-bars 24 are placed upon both sides of engines, to be used on single-track roads, and are arranged parallel with each other and with the level of the track, so that in whatever direction the engine be moving, and whether running forward or backward, it will operate proper signals upon one or the other side of the track.

Between the lower arms, D D' D², and the ground-wires L are interposed lightning-arresters 31, to prevent the signals from being operated and the electric apparatus injured by atmospheric electricity.

The operating parts of the apparatus are designed to be covered by casings to protect them from injury.

The combination of the oscillatory signal J³ with an advance signal, J, hooked armature M, and disk or lever k, having shoulder or hook l, will be made the subject of a subsequent application for patent.

Having thus described my invention, I claim as new and desire to secure by Letters Patent—

1. A system of electric railway-signals com-

prising a series of normally-independent circuits, each of which is connected at either end with electric signal-controlling mechanism, including a normally-grounded switch and a 5 visual signal adapted to be displayed by mechanically-stored power, released electrically, and then mechanically housed, and means, substantially as set forth, whereby each display movement of the said signal will break 10 the ground-connection of its system and unite the contiguous normally-independent circuits.

2. A system of electric railway-signals comprising separate line-circuits connected in series, signal-controlling devices located at each 15 signaling-station and connected with each section of the series and provided with electric signal-operating mechanism, including a normally-open ground-switch and a visual signal adapted to be mechanically displayed and then 20 housed by mechanically-stored power, released electrically, and means, substantially as described, whereby each display movement of the signal will complete the ground-connection of its circuit, thereby disuniting the contiguous 25 circuits.

3. An electric railway-signal system comprising a series of separate normally-independent circuits, each of which is connected at one end with electric signal-controlling mechanism 30 for advance signals, and at its other end with electric signal-controlling mechanism for rear signals, a switch normally grounded and located in proximity to the advance signal, and mechanical connections between said signal 35 and the switch, whereby the latter is automatically shifted so as to span the signal-operating mechanism and unite the contiguous circuits upon the displaying of the signal, as set forth.

4. In a system of railroad-signaling, a series 40 of separate normally-independent circuits, each of which includes a movable ground-connection normally out of circuit, a rear signal and electro-mechanical devices for retaining same in its displayed position, and mechanical connections between said signal and the movable earth-circuit, whereby the latter is only brought into action during the exposure of the signal, and is automatically cut out when the 50 same is released and allowed to fall, substantially as described.

5. In electric railway-signals, a series of signaling-stations extending along a line of railway, each provided with a normally-grounded movable contact, and means, substantially such as described, for transmitting a current from a moving train at one of the rear posts to one or more thereof in advance and to ground successively through the said 55 movable contacts, and a signal-controlling electro-magnet located at each of said stations, said ground-connections being successively broken by the displaying of the signals released therethrough, as set forth.

6. A system of electric railway-signals comprising a series of separate normally-independ-

ent circuits, each including a movable temporary ground-connection at its advance signaling-point, and means, substantially as described, whereby said ground-connection is 70 placed under compression by the displaying of said advance signal, and thereby automatically cut out of circuit, as set forth.

7. A system of electric railway-signals comprising a series of separate normally-independent circuits, each including a movable temporary ground-connection at its advance signaling-point, said ground-connection being brought into circuit by the attraction of the armature of an electro-magnet, and then put 75 under compression while so connected by the change of position of a signal released by said armature, so that it will move out of contact position when said armature is released, and remain out of contact position until said signal is returned to its normal position, as set forth.

8. In an electric railway-signaling system, the combination, with an electro-mechanically-controlled advance signal, of an oscillatory 90 signal for highway and other crossings secured to the axis of said advance signal and at right angles thereto, and moved upon its horizontal longitudinal axis from "danger" to "safety," and vice versa, by the ordinary manipulations 95 of the advance signal, as set forth.

9. In electric railway-signals, the combination, with the armature-operated conducting wire or strip T and the switch U, of the switch I, lever P, and signal J, substantially as herein shown and described, whereby the free end of the switch U is forced out of contact position by the downward movement of the advance signal, as set forth.

10. In electric railway-signals, the combination, with the conducting-wires F H E and the ground-wire L², of the armature-operated conducting wire or strip T, the switches U I I', the signals J J', levers P P', and the conducting-wire W, substantially as herein shown and described, whereby the forward ground-connection is changed from post to post automatically in advance of the train, as set forth.

11. In electric railway-signals, the combination, with the rear signal, J', having pin d, the armature M', having hook N', and the magnet G', of the lever P', having curved recess b, slot e, and hook O', substantially as herein shown and described, whereby the said signal is held in place when displayed, and released by the passage of an electric current through the said magnet, as set forth.

12. In electric railway-signals, the combination, with the armature M, having hook N', the signal J, having pin S, and the magnet G, of the bent lever P, having hook O, and slot R, substantially as herein shown and described, whereby the advance signal is held in place when concealed, and is released by the passage of an electric current through the said magnet, as set forth.

13. In electric railway-signals, the combination, with the sliding rod 17, operating the weight-raising elbow-lever 12, and the supports 18, of the two springs 19 20, and the pins 21 22, substantially as herein shown and described, whereby the said rod will be brought back to its normal position after being moved in either direction, as set forth.
14. In electric railway-signals, the combination, with the horizontally-sliding rod 17, the elbow-lever 12, and the vertically-sliding rod *z*, having clutch-jaws 4, of the rod 8, the sliding weight 7, carrying the rod 6, having spear-head end 5, and the stops 27 and 28, substantially as herein shown and described, whereby the weight is raised and suspended by the

action of a passing train, and is released by the descent of the vertically-sliding rod, as set forth.

15. In electric railway-signals, the combination, with the signals J J', having stop-pins 26, and the vertically-sliding rod *z*, having slotted horizontal arms *y y'*, of the pivoted connecting-bars *x x'*, substantially as herein shown and described, whereby the said signals will be raised by the downward movement of the said rod, as set forth.
